UNITED STATES PATENT OFFICE.

JOHN A. CONTOS, OF GRAND ISLAND, NEBRASKA, ASSIGNOR OF ONE-HALF TO NICK JAMSON, OF GRAND ISLAND, NEBRASKA.

TABLE FOR AUTOMOBILE-RADIATORS.

1,382,626.

Specification of Letters Patent. Patented June 28, 1921.

Application filed July 29, 1920. Serial No. 399,771.

To all whom it may concern:

Be it known that I, JOHN A. CONTOS, a citizen of the United States, residing at Grand Island, in the county of Hall and 5 State of Nebraska, have invented a new and useful Table for Automobile-Radiators, of which the following is a specification.

This invention relates to work supporting tables, and more particularly to a work 10 support designed to be employed in motor vehicle repair.

The primary object of the invention is to provide a device of this character for supporting the article under operation, the device 15 being of an adjustable nature to permit the article supported to be moved to various angles to permit of the repair of the same, with facility.

A further object of the invention is to 20 provide clamping means adapted to be adjusted with relation to the body of the table so that the support may be employed for clamping articles of various designs.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

Referring to the drawing:

Figure 1 illustrates a plan view of the 35 table constructed in accordance with the present invention.

Fig. 2 illustrates a side elevational view, and

Fig. 3 illustrates a fragmental sectional view disclosing the means for supporting the upper portion or top thereof.

Referring to the drawing in detail, the reference character 5 designates the base of 45 the work supporting table which includes the spaced arms 6 for supporting the base, the base being also provided with an upwardly extending pin 7 by means of which the upper portion of the work support may 50 be rotated about the base 5.

The standard 8 which connects the table top and base 5, is relatively long and provided with an opening extending inwardly from the lower end thereof, which opening 55 is designed to accommodate the pin 7 to permit of rotary movement of the standard

with relation to the base 5, to accomplish one of the adjustments of the work support.

Formed at the upper extremity of the standard 8 is an opening adapted to accommodate the transversely extending pin 9, which has its ends positioned in suitable openings provided in the forked extremity of the vertical pin 10, which vertical pin also extends through the cross arms 11 to permit 65 of rotary movement of the upper portion of the device with relation to the standard 8, there being provided a nut 12 on one end of the pin 10, for securing the upper portion of the device in various positions.

As shown, the cross arms 11 have connection with the circular member 13 which is provided with a plurality of openings 14, the openings being of sizes to accommodate the sliding bolt 15 supported by the arm 16, 75 forming one of the cross arms and which is slightly longer than the remaining arms to support the sliding bolt 15, so that the cross arms may be moved circumferentially of the member 13 to accomplish still another 80 adjustment of the support.

The circular member 13 also rests on the cross arm 17, which is provided with an opening to accommodate the pivot pin 10, to permit the arm 17 to rotate, the semi-circular bar 18 which has its upper ends connected to the arms 17 being provided to secure the upper portion of the support in various positions of adjustment. This semi-circular bar 18 is provided with a plurality 90 of notches adapted to receive the rib 19 so that the upper portion of the device may be rocked, and the rib 19 positioned in one of the cut out portions 20 to secure the upper portion of the device at an angle with relation to the standard 8.

Adjustable clamping elements indicated by the reference character 21 operate on the arms 11 and 16, each of which clamping elements includes an upwardly extending arm 22 and a pivoted arm 23, connected in any suitable manner to permit the arms 23 to swing with relation to the arm 22 associated therewith, so that the clamping elements may be adapted for use with articles of various 105 designs.

In the operation of the device, assuming that a motor vehicle radiator is to be repaired, the radiator is clamped by the clamping members 20, and the member 18 moved 110 to bring the radiator at the proper angle to permit the repair of the same with facility.

The support may now be moved to bring the opposite side of the radiator up, to permit the same to be repaired.

Having thus described the invention, what is claimed as new is:—

1. A work supporting table including a base, said base having a pin extending upwardly therefrom, a standard having an opening formed in one end thereof, to accommodate the pin, cross arms having pivotal connection with the standard, a circular member having openings formed therein, means carried by one of the cross arms and adapted to be positioned in one of the openings to secure the cross arms in various positions of adjustment, and adjustable clamping members carried by the cross arms.
- 10
- 15

2. A work supporting table including a base, said base having a pin extending upwardly therefrom, a standard having an opening formed in one end thereof to accommodate the pin, cross arms having pivotal connection with the standard, a circular member having openings formed therein, and adjustable clamping elements supported on the cross arms.

In testimony that I claim the foregoing as my own, I have hereto affixed my signature in the presence of two witnesses.

JOHN A. CONTOS.
